SHADE ROLLER CHECK

Filed Aug. 6, 1936

UNITED STATES PATENT OFFICE

2,119,408

SHADE ROLLER CHECK

James M. Wilson, Newark, N. J., assignor, by
mesne assignments, to Shade Check, Inc.,
Newark, N. J., a corporation of New Jersey

Application August 6, 1936, Serial No. 94,559

6 Claims. (Cl. 156—36)

This invention relates particularly to spring actuated window shade rollers, and more especially to a check for preventing rotation of the roller under the influence of the spring at a speed in excess of a predetermined limit, for example when a shade escapes from the hand of the person raising or lowering the shade. However, the invention is equally susceptible to other types of spring operated rollers.

One object of the invention is to provide a novel and improved check of the character described which shall include a part projected from one end of the roller into a position to engage a stationary support or part, for example a shade bracket, by centrifugal force caused by rotation of the roller at excessive speed so as to stop rotation of the roller.

Another object is to provide such a check which shall include a stop dog mounted on one end of the roller and normally permitting rotating thereof at a speed below a predetermined limit, and an actuator mounted on the roller and operated by centrifugal action upon rotation of the roller at a speed in excess of said limit to project said dog from the end of the roller into position to engage a support and stop rotation of the roller.

Other objects are to provide a shade roller check unit which can be easily and quickly applied to the end of a roller opposite the usual controlling pawls and ratchets so that the unit can be supplied to users of shade rollers for application to rollers already in use, and to obtain other advantages and results as will be brought out by the following description.

Referring to the drawing,

Figure 1 is a top plan view of a shade roller installed in brackets and having a check embodying my invention applied thereto.

Figure 2 is a sectional view on an enlarged scale taken on the line 2—2 of Figure 1.

Figure 3 is a view similar to Figure 2 with the end of the check casing removed and with the stop dog and actuator in normal position.

Figure 4 is a view similar to Figure 3 showing the stop dog projected from the roller to stop rotation of the same.

Figure 5 is a transverse sectional view through the casing only on the line 5—6 of Figure 3 and showing the stop dog and actuator in side elevation.

Figure 6 is a complete transverse sectional view on the line 5—6 of Figure 3.

Figure 7 is a transverse sectional view through the casing only on the line 7—7 of Figure 4,

showing the stop dog and actuator in side elevation.

Figure 8 is an end elevation of the roller and the stationary support showing the engagement of the stop dog with the support to stop the roller.

Figure 9 is a horizontal sectional view through the casing only on the line 9—9 of Figure 7 showing the manner of returning the stop dog to normal position.

Figure 10 is an inside elevation of the cover plate of the check casing.

Figure 11 is a view similar to Figure 5 but on a reduced scale, showing a slightly modified construction, and

Figure 12 is an end view of Figure 11 looking from right to left.

Specifically describing the invention the reference character A designates a spring operated shade roller of known construction having the usual controlling pawl and ratchet mechanism B at one end, a fixed shaft C and a rotatable trunnion D at its opposite ends mounted in stationary supports or brackets E. Within the roller is the usual spring F for normally rotating the roller in one direction, for example to wind the shade thereon, the spring being tensioned or wound by rotation of the roller in the other direction as in lowering the shade.

At the end of the roller opposite the controlling pawls B is the check embodying my invention. This check is shown as including a casing G composed of two telescopically connected cup shaped sections 1 and 2. The casing is secured to the end of the roller in any suitable manner as by screws 3 passing through the casing, and preferably the trunnion D is secured to the casing between the casing sections, as by a shoulder 4 clamped between the sections, and has a pointed portion 5 driven into the roller.

Within the casing is a stop dog 6 which is pivotally mounted on a pin 7 in a bracket 70 on an axis perpendicular to the axis of the roller and casing so that the dog may lie wholly within the casing as shown in Figures 3 and 5 or may be projected about its pivot from the casing through an opening 2a therein, as shown in Figures 4 and 7.

An actuator lever 8 is pivotally mounted between its ends in the casing on a pin 9 on an axis parallel with the axis of the roller and the casing to be swung about its pivot by centrifugal action upon the rotation of the roller and casing. One end of the actuator lever has a cam surface 10 cooperating with a cam surface 11 on the stop dog for initiating the projection of the dog about its pivot outwardly of the casing upon rotation.

of the roller and casing at a speed in excess of a predetermined limit. The pivoted end of the dog has a shoulder 12 to engage the bracket and limit pivotal movement of the dog outwardly of the casing as clearly shown in Figure 9, and a spring 13 is secured in the casing to abut said shoulder and hold the dog in normal position within the casing as shown in Figure 3.

In operation, when the roller is rotated against 10 the influence of the spring to lower the shade, or under the influence of the spring to raise the shade at a normal speed below a predetermined limit the stop dog is positioned within the casing so as to permit the free rotation of the roller, 15 as shown in Figures 2 and 4. Should the shade escape from the hand of the person adjusting it, or get out of control for any reason and revolve under the influence of the spring at a greater than normal speed or in excess of a predetermined 20 speed, the centrifugal force set up by rotation of the roller will swing the actuator lever 8 as shown in Figure 4 so as to cause sudden engagement of the cam surfaces 10 and 11 of the actuator and the dog and swing the free end of 25 the dog out of the casing whereupon centrifugal action will project the dog out of the casing from and beyond the end of the roller into a position to engage the edge of the adjacent stationary support or bracket E and thereby stop rotation 30 of the roller as shown in Figure 8. Upon rotation of the roller in the opposite direction to unwind or lower the shade, the dog will engage the opposite edge of the stationary support E and be returned into the casing, Figure 9 illustrating the position of the dog just prior to engagement thereof with the support E during this 35 operation. Preferably the dog will have a cam surface 15 to engage the support E and facilitate this action.

40. In Figures 11 and 12, the parts 1 and 2 are held together by fingers 16 which are on the part 1 and are adapted to be bent over the top surface of the member 2. The trunnion D while having the flange 4 outside the member 2 may be 45 held in place by frictional engagement with the other parts through or into which it is driven, or by brads 17.

It will thus be seen that the invention provides 50 a reliable simple and inexpensive check to prevent "running away" of a spring operated roller under the influence of the spring, and the check constitutes a unit which may be applied to different rollers as desired without modification of the roller.

55. While the form of the invention herein described is the now preferred form, it should be understood that it is primarily for the purpose of illustrating the principles of the invention and that many modifications and changes may be made in the details of structure without departing from the spirit or scope of the invention.

Having thus described my invention, what I claim is:

60. 1. The combination with a spring actuated roller and a stationary support therefor at one end, of means for checking the roller upon rotation thereof under influence of the spring at a speed in excess of a predetermined limit said means comprising a stop dog pivotally mounted on said roller on an axis perpendicular to the axis of the roller and normally permitting rotation of the roller at a speed below said limit, and an actuator lever pivoted on said roller on an axis parallel to 65 the roller axis to be swung about its pivot by cen-

trifugal action upon rotation of said roller, said actuator and said dog having cooperating cam surfaces whereby upon rotation of the roller at excessive speed the dog is projected about its pivot into a position to engage said stationary support and stop rotation of the roller. 5

2. A spring roller check unit of the character described comprising a casing to be secured coaxially to one end of a spring roller, a stop dog pivotally mounted in said casing on an axis perpendicular to the axis of the casing and normally disposed within the casing and an actuator lever pivotally mounted in said casing on an axis parallel to the casing axis to be swung by centrifugal action upon rotation of said casing at a speed about its axis in excess of a predetermined limit, said dog and actuator lever having cooperating cam surfaces to project said dog about its pivot outwardly from the casing upon rotation of the casing at a speed in excess of said limit. 20

3. A spring roller check unit of the character described comprising a casing to be secured coaxially to one end of a spring roller, a stop dog pivotally mounted in said casing on an axis perpendicular to the axis of the casing and normally disposed within the casing, and an actuator movably mounted in said casing to be operated by centrifugal force upon rotation of said casing about its axis at a speed in excess of a predetermined limit, said dog and said actuator having cooperating cam surfaces engageable upon such operation of said actuator by centrifugal force to project said dog about its pivot outwardly from the casing upon rotation of the casing at a speed in excess of said limit. 30

4. The combination with a spring actuated roller and a stationary support therefor at one end, of means for checking the roller upon rotation thereof under influence of the spring at a speed in excess of a predetermined limit, said means comprising a stop dog pivotally mounted on said roller on an axis perpendicular to the axis of the roller and normally permitting rotation of the roller at a speed below said limit, and an actuator movably mounted on said roller to be operated by centrifugal force upon rotation of said roller about its axis in excess of a predetermined speed, said dog and said actuator having cooperating cam surfaces engageable upon such operation of the actuator by centrifugal force to project said dog about its pivot into a position to engage said stationary support and stop rotation of the roller. 40

5. The combination with a spring actuated roller and a stationary support therefor at one end, of means for checking the roller upon rotation thereof under influence of the spring at a speed in excess of a predetermined limit, said means comprising a stop dog pivotally mounted on one end of said roller on an axis perpendicular to the axis of the roller and normally permitting rotation of the roller at a speed below said limit, and an actuator movably mounted on said end of the roller to be operated by centrifugal force upon rotation of said roller about its axis in excess of a predetermined speed, said dog and said actuator having cooperating cam surfaces engageable upon such operation of the actuator by centrifugal force to project said dog about its pivot from said end of the roller into a position to engage said stationary support and stop rotation of the roller. 55

6. The combination with a spring actuated roller and a stationary support therefor at and beyond one end thereof, of means for checking 70

the roller upon rotation thereof under influence of the spring at a speed in excess of a predetermined limit, said means comprising a stop dog mounted on said end of the roller to normally clear said stationary support and to move in a direction parallel to the axis of the roller to project from said end of the roller into position to

engage said stationary support and stop rotation of the roller, and means operated by centrifugal force for so projecting said dog from the end of the roller upon rotation of the roller at excessive speed.

JAMES M. WILSON.
